UNITED STATES PATENT OFFICE.

SIMON FREY, OF ZURICH, SWITZERLAND.

THREAD-CUTTING APPARATUS.

1,026,205.

Specification of Letters Patent. Patented May 14, 1912.

Application filed November 2, 1911. Serial No. 658,201.

To all whom it may concern:

Be it known that I, SIMON FREY, a citizen of the Swiss Republic, and a resident of 17 Mythenstrasse, Zurich, Switzerland, have invented certain new and useful Improvements in Thread-Cutting Apparatus, of which the following is a specification.

This invention relates to improvements in actuating and lubricating means for thread cutting devices of the character employing a plurality of dies, each having thread cutting faces thereon, the entire apparatus being embodied in a single composite structure.

The invention will be more fully described in connection with the accompanying drawings and will be more particularly pointed out in and by the appended claims.

In the drawings:—Figure 1 is a view, partly in section and partly in elevation, of an apparatus embodying my invention. Fig. 2 is a sectional view on the line A—B of Fig. 1. Fig. 3 is a view partly in elevation and partly in section, of a portion of the apparatus shown in Fig. 1. Figs. 4 and 5 are enlarged detailed sectional views of parts of the apparatus shown in Fig. 1.

Similar characters refer to similar parts throughout the several views.

In carrying out this invention, and referring to the drawings, a stock body *a* is provided with a square frame *b*, for the reception of coacting dies 1, 2, 3 and 4, and two oil cavities *c* and *d*. The stock body *a* is circular with respect to its plane and has provided on its periphery, radially extending rectangular-shaped recesses *A*. The periphery of the stock is surrounded by a band *B*, which, at its inner circumference, has, at one edge, a projection *B'* engaging in a groove *a'* in the stock. This projection *B'* has at its inner side an annular groove *B''*, which communicates with oil receptacles *c* and *d* by means of by-passes *a'* in the frame *b*.

The band *B* is provided with an aperture *b'* which is disposed in alinement with the apertures *A* in the stock and extends to the projection *B*. Through this aperture *b'* projects a pawl *C* adapted to oscillate on a pivot *C'* and is located within a cavity *C°* of a handle socket *D* secured to the band *B* by means of countersunk screws *S*. The end of the said pawl gliding on the circumference of the stock in the central position, so engages in the recesses *A*, that when turning the handle socket by the aid of a tube *e*

screwed into it, the stock with the dies will be turned around the piece of work, as for example, a pipe, inserted between the latter. In order to cause the said pawl to have the tendency of always taking a central position, that is to say, a position radial to the stock, a coiled spring *F* is provided on each side thereof, which acts upon laterally projecting arms *C'* on the pawl. From each side of the said handle socket set screws *G* and *G'* project into the cavity *C°* toward the said pawl arms, whereby the oscillation of the pawl can be restricted to one side only or the pawl rendered inoperative. The adjustment of the said screws, thus facilitates the use of the stock and dies in either ratchet brace fashion or in ordinary handle fashion.

Suitably apertured face plates *a'* and *a''* are provided for the stock *a*, which form fluid tight compartments of the cavities *c* and *d*. The handle socket *D* has a channel *H* branching from the middle to each side. This channel leads to the groove *B''* of the projection of the band *B* and is in communication with the interior of the tube *E* forming part of the handle. The free end of the latter is closed by means of a tightly fitting detachable cap *J* and contains a piston *K* inwardly movable by a coiled spring *K'*. This piston serves to force lubricating fluid into the tube *E* through the channel *H* into the groove *B''*, from whence it passes through the slots *a'* into the oil receptacles *c* and *d*, and from there through the frame *b* to the dies as will be subsequently described.

The two receptacles *c* and *d* are arranged in communication with each other by means of a slot *p* so that the lubricant contained therein can pass to and fro. In the slot *p* is a conical plug *q* having a portion semi-circular in section whereby lubricant can be passed from either of the receptacles *c* and *d* through the slot *p* into a port *r* formed in communication therewith in the frame *b*. The side of the die 3 bearing against the frame *b* is provided with a flat recess *f* from which a port *t* leads to the cutting surface of the die 3. The fluid which enters the port *r* flows into the recess *s* and from there through port *t* to the cutting surface of the die 3, where it issues and thus lubricates the surface of the work to be operated upon to facilitate the cutting. The recess *s* is of such a length that there is no position of adjustment of the die in which it will be cut off

from the port r . The plug q can be turned and thus the port r is opened or closed.

The handle socket D has two lateral projecting portions L . Between these portions 5 and the band B a space is provided into which projects the ends of a band M , each of the ends having an aperture, as shown in Fig. 1, and which is detachably secured to the handle socket D and the band B by 10 means of screws N . Diametrically opposite the handle socket D , a handle D' is secured to the band M by means of screws. After turning back the screws N , the band M with a handle D' can be removed from 15 the stock a as indicated in dotted lines of Fig. 3, and the stock and dies operated with a single handle.

On the lower edge of the band B is an extension b'' which fits accurately into a ring 20 like groove of the cover a^5 and forms a joint preventing the oil leaving the surface of the stock and dies.

The stock and dies described may be turned at will with one of two handles in 25 either direction and a continuous supply of lubricant is provided for the operating dies under any condition.

I claim:—

1. A thread cutting apparatus comprising 30 in combination, a drum-shaped stock provided with a plurality of recesses in the periphery thereof and a fluid chamber, a die carried by said stock and provided with a fluid conducting port open to the cutting 35 edge thereof and communicating with the said fluid chamber of said stock, a band surrounding the periphery of said drum, movable therewith, and provided with fluid conducting means communicating with its 40 periphery and the said fluid chamber in said stock, a handle structure secured to said band and provided with a cavity adapted to contain fluid and in communication with the fluid conducting means of said band, 45 and a ratchet pawl carried by said handle structure and coacting with the said recesses in the periphery of said stock to operate the apparatus.

2. A thread cutting apparatus comprising 50 in combination, a drum-shaped stock provided with a plurality of recesses in the periphery thereof and a fluid chamber, a die carried by said stock and provided with a fluid conducting port open to the cutting 55 edge thereof and communicating with the said fluid chamber of said stock, a band surrounding the periphery of said drum, movable therewith, and provided with fluid conducting means communicating with its 60 periphery and the said fluid chamber in said stock, a handle structure secured to said band and provided with a cavity adapted to contain fluid and in communication with the fluid conducting means of said band, a 65 ratchet pawl carried by said handle struc-

ture and coacting with the said recesses in the periphery of said stock to operate the apparatus, and means for fixing said pawl in one of said recesses to rigidly connect said handle structure and said stock.

3. A thread cutting apparatus comprising 70 in combination, a drum-shaped stock provided with a plurality of recesses in the periphery thereof and a fluid chamber, a die carried by said stock and provided with a fluid conducting port open to the cutting edge thereof and communicating with the said fluid chamber of said stock, a band surrounding the periphery of said drum, movable therewith and provided with fluid conducting means communicating with its periphery and the said fluid chamber in said stock, a handle structure secured to said band and provided with a cavity adapted to contain fluid and in communication with the fluid conducting means of said band, a 75 spring actuated piston within the said cavity for feeding the fluid to said die, and a ratchet pawl carried by said handle structure and coacting with the said recesses in 80 the periphery of said stock to operate the apparatus.

4. A thread cutting apparatus comprising 85 in combination, a drum shaped stock provided with a plurality of recesses in the periphery thereof and a fluid chamber, a die carried by said stock and provided with a fluid conducting port open to the cutting edge thereof and communicating with the said fluid chamber of said stock, a band 90 surrounding the periphery of said drum, movable therewith, and provided with fluid conducting means communicating with its periphery and the said fluid chamber in said stock, a handle structure secured to 95 said band and provided with a cavity adapted to contain fluid and in communication with the fluid conducting means of said band, a second handle structure adapted to be disposed diametrically opposite said first mentioned handle structure with respect to 100 said stock, and provided with means for embracing said band and securing said second mentioned handle structure to said first mentioned handle structure, and a ratchet 105 pawl carried by said first mentioned handle and coacting with the said recesses in the periphery of said stock to operate the apparatus.

5. A thread cutting apparatus comprising 110 in combination, a drum shaped stock provided with a plurality of recesses in the periphery thereof and a fluid chamber, a die carried by said stock and provided with a fluid conducting port open to the cutting 115 edge thereof and communicating with the said fluid chamber of said stock, means adapted to control admission of fluid into the conducting port of said die, a band surrounding the periphery of said drum, mov- 120

able therewith, and provided with fluid conducting means communicating with its periphery and the said fluid chamber in said stock, a handle structure secured to said band and provided with a cavity adapted to contain fluid and in communication with the fluid conducting means of said band, and a ratchet pawl carried by said handle structure and coacting with the said recesses

in the periphery of said stock to operate the apparatus.

In testimony whereof I affix my signature in presence of two witnesses.

SIMON FREY.
